UNITED STATES PATENT OFFICE.

EDWARD FRANCIS McHUGH, OF KINGSTON, PENNSYLVANIA.

VENTILATING SASH.

Application filed February 25, 1925. Serial No. 11,569.

This invention relates to improvements in 5 ventilating sashes for use upon store fronts in supporting plate glass windows and contemplates the provision of a novel form of supporting means which will resiliently support the lower edge or edges of the plate glass in order to take up vibrations, knocks, and jars and the like in order to prevent cracking of the glass.

10 Another object of the invention is to provide draining means upon the inner side thereof whereby upon the washing of the inside of the plate glass the water will run down the glass and through the openings 15 and thence outwardly and over the sill covering so that the floor will not be subjected to standing water.

A further object of the invention is the 20 provision of a novel form of back member which is secured to a backing stop forming the front edge of the floor display window and which includes an upwardly crimped portion upon the lower side thereof which 25 will provide a seat for a supporting member thereon and which has spaced from the upper edge thereof the lower edge of a plate glass window through the instrumentality 30 of a resilient packing or the like whereby a triple resiliency is provided beneath the lower edge of the plate glass window in order that all shocks, jars and the like will be prevented so that the glass will not be broken when subjected to such treatment.

With the above and other objects in view, 35 the invention further includes the following novel features and details of construction, to be hereinafter more fully described, illustrated in the accompanying drawing and pointed out in the appended claims.

40 In the drawing:—

Figure 1 is an end view of a portion of a window showing the present invention applied thereto and supporting a plate glass thereon.

45 Figure 2 is a detail perspective of the back member per se.

Referring to the drawing in detail, 50 wherein like characters of reference denote corresponding parts, the reference character 10 indicates the sill and 11 the backing stop of the store window and to which the present invention is applied.

The present invention embodies a back member 12 which has its upper edge downwardly and outwardly inclined as at 13 and

includes a plurality of ventilating or drain holes or openings 14 therein and is then bent upwardly and vertically thereon. The lower edge of the back member 12 is bent upwardly upon itself as at 15 to provide a longitudinal supporting edge or leg as shown and thence extends into an outwardly horizontally extending cushion portion 16 and has its outer edge crimped inwardly as at 17 and thence downwardly to provide a supporting edge or leg 18 whereby the cushioning member or portion 16 is spaced and held in spaced relation from the sill as shown in Figure 1 of the drawing. Positioned upon the upper side of the cushion portion 16 of the back 70 member 12 is a substantially inverted U-shaped supporting member or setting block 19 which includes upon the upper edge thereof a cushioning layer which may be formed of fabric or leather, and which is indicated 75 as at 20, and which is adapted to receive thereon the lower edge of a plate glass or the like 21. These supporting members 19 are arranged in spaced relation upon the cushion portion 16 and vary in number, according to the size and weight of the glass.

In order to provide means upon the outer side of the plate glass 21 for holding the same upon the cushioning member 19 and leather support 20, I provide the usual and 80 ordinary type of outer moulding 22 and which has extending at an inclination therefrom suitable fastening elements in the form of screws 23 which in turn extend between the supporting member 19 and 85 through slots 24 provided upon the vertical portion of the back member 12 whereby the inner end portion of the screw member 23 may be embedded in the backing stop. The back member 12 further includes openings 90 25 which may receive nails, screws and the like therethrough for holding the same rigidly and vertically upon the backing stop.

In this invention, I also employ a sill covering 26 which extends along an appreciable 100 distance upon the upper side of the sill 10 and terminates in an upturned flange 27 arranged in the rear of and in contacting engagement with the downwardly extending edge or leg 18 of the cushioning member 16 105 in order to provide a rigid support for this edge and in order to prevent the same from becoming embedded within the upper side of the sill 10 when subjected to the weight of the plate glass 21. The outer moulding has 110

its inner lower edge arranged in contacting engagement with the edge 18 and below the inwardly crimped portion 17, and as clearly shown in Figure 1, the flange 27, the edge 18, and the inner lower edge of the outer moulding interlock to provide a water proof joint and prevent movement of the parts.

It will thus be noted from the foregoing description and accompanying drawing that a person within the store window when washing the plate glass 21 will cause water to drain downwardly upon the inner side of the glass 21 and into the gutter formed upon the upper edge of the back member 12 as indicated at 13 and flow or drain through the ventilating or drain holes, or openings 14 provided therein and will thence find its way between the backing member 12 and the outer moulding 22 through the opening 27 provided adjacent the lower edge thereof whereby the water or moisture will be drained outwardly and upon the sill covering 26 in order that no moisture will be allowed to stay between the back member 12 and outer moulding 22 which would deteriorate or destroy the ventilating sash.

It is also to be noted that this invention provides an exceedingly useful as well as advantageous support for plate glass inasmuch as the cushioning portion 16 provided by the crimpings on the back member 12, supports the supporting member 19 thereon which in turn carries a fabric or leather strip 20 upon the upper side thereof which supports or engages the lower edge of a plate glass window 21 and the like in order to prevent cracking of the glass when the same is subjected to vibrations, shocks, jars and the like.

The invention is susceptible of various changes in its form, proportions and minor details of construction, and the right is herein reserved to make such changes as properly fall within the scope of the appended claims.

Having described my invention what is claimed is:

1. A ventilating window sash, a back member secured to the window backing stop, a raised cushion portion horizontally disposed and formed with the lower edge of the back member, said cushion portion terminating at its forward edge in a crimped downwardly extending supporting leg, and also with a supporting leg at its juncture with the back member, a sill covering for the sash and receiving the forward supporting leg of the cushion portion, a substantially inverted U-shaped setting block mounted upon the cushion portion, resilient means carried by said block and adapted for receiving the lower edge of a plate glass, and an outer moulding secured to the backing stop and mounted upon the sill covering in a manner whereby the upper portion of said moulding engages the glass, and its lower portion disposed relatively with the crimped downwardly extending supporting leg to prevent upward and rear movement of the lower portion.

2. In a ventilating window sash, the combination with a sill and a backing stop, a back member secured to the sill, a cushion portion formed on the back member, supporting legs for spacing the cushion portion from the sill and one of said supporting legs being bent inwardly and thence downwardly upon itself, a covering for the sill and terminating at its inner end in an upturned flange arranged to the rear of and in contacting engagement with the downturned portion of the last mentioned supporting leg, and an outer moulding cooperating with the back member and having its lower edge arranged in contacting engagement with the downturned portion and below the inwardly extending portion of said supporting leg.

In testimony whereof I affix my signature.

EDWARD FRANCIS McHUGH
